 The American Laundry Machinery Company,
 Cincinnati, Ohio, a corporation of Ohio

Application December 22, 1930, Serial No. 504,007

3 Claims. (Cl. 68—9)

My invention relates to pressing machines and, particularly to operating mechanism for a pressing machine including a work supporting bed and a head movable into cooperative relation therewith to bring about a pressing action.

In presses of this type, the pressing head is normally separated a sufficient distance from the work supporting bed so that work may be conveniently placed thereon or removed therefrom and with sufficient space between the pressing head and work supporting bed to permit clear visibility of the pressing bed or the work thereon when the bed and head are out of cooperative relation and the machine is not in operation. The actual pressing action in a press of the type disclosed by my invention takes place at the final movement of the pressing head to exert pressure on the pressing bed after it has been moved into cooperative relation therewith at any desired speed and it is at this period of the operation that the actual high pressure is applied, the greater part of the movement of the head requiring only sufficient moving force to overcome the force exerted by springs or other means employed to return the head to its open unoperated position at the end of a pressing operation.

One object of my invention is to provide an operating mechanism for a pressing machine of the above type wherein the initial moving force for moving the head into cooperative relation with the work supporting bed is relatively small which permits the employment of manual means without diminishing the speed of operation of the press and takes place only a comparatively short length of time which is conducive to relatively short operation of the manual operating means, for instance a short throw of a lever, yet the head of the press will be moved through the usual long arc about a pivot and be forced to its final position under a very high pressure. Thus a quick operating press may be provided without necessitating what is termed as a full automatic operating means.

Another object of my invention is to provide an operating mechanism whereby a very small movement of the part which causes the initial operation or pressing engagement of the head with the bed, for instance a foot pedal and lever, will give the desired result and to provide a simple and durable device which will permit economy of force required in producing the desired results both as relate to initial engagement of the pressing members and the final pressure or "squeeze" between the members

during which last action the actual pressing operation takes place.

Various other objects and advantageous features of my invention will be seen in the following description and one embodiment thereof may be seen in the accompanying drawings wherein similar characters of reference designate corresponding parts, and wherein:

Fig. 1 is a side elevation, partly in section, of a pressing machine embodying my invention showing the head in its normal unoperated position; Fig. 2 is a similar view showing the head down against the buck or pressing bed in operated position; and Figs. 3 and 4 are views showing the motor control valve in detail.

Referring to the drawings, I have shown one embodiment of my invention as comprising a buck 1 which, as usual, is rigidly secured on top of a standard or frame 2 provided with rearwardly and upwardly extending supports 3 having a cross shaft 4 secured to the upper ends thereof. A hub 5 having four radiating arms 6, 7, 8 and 9 is pivotally mounted on the shaft 4, the arms 7 and 8 being bifurcated to avoid interference with centrally located operating mechanism and to add rigidity thereto. The usual pressure or pressing head 10 is mounted on the extremity of the arm 6 in such position that the lower surface of the pressure or pressing head will register with the inclined top of the buck 1 when the head is in its lowered or closed position as shown in Fig. 2.

It will be noted that the arm 9 is substantially shorter than the arms 6, 7 and 8, the arm 7 acting only as a support for a weight 11 which over-balances the weight of the head 10 and tends to move it to open position, and is forked at its outer end whereby it may receive a pivotally mounted block 12 having a perforation or a substantially vertically extending opening therein, the block being supported between the prongs 13 of the forked end of the arm. Likewise, it will be noted that the arms 8 are substantially longer than either of the arms 6 or 9 and have a pair of links 14 pivotally connected to their free ends as at 15. The other ends of the links 14 are, in turn, pivotally connected to the free end of an arm 16 as at 17 and the other end of the arm 16 is, in turn, pivotally connected as at 18 to the lower part of the frame 2.

As will be clearly apparent, the links 14 form one-half of a toggle structure while the arm 16 forms the other half of the same toggle which is disposed between a point on the frame 2 and the free end of the relatively long arms 8 and the arrangement of the parts is such that

the toggle is in a substantially straight line between the pivot point 18 of the arms 16 and the pivotal connection 15 between the links 14 and the relatively long arm 8 when the pressure or 5 pressing head 10 is in cooperative relation with the buck or pressing bed 1. Therefore, a small amount of pressure downwardly on the pivot 17 will cause a relatively great pressure downwardly on the buck or pressing bed 1 by the pressure 10 or pressing head 10 as will be clearly seen in Fig. 2. This is due, primarily, to the mechanical advantage of the toggle.

The operating means for moving the pressure or pressing head 10 into initial engagement with 15 the padded bed or buck 1 consists, in this instance, of a foot treadle or lever 19 pivotally mounted on the frame 2 as at 20 and having a link 21 pivotally connected thereto as at 22 and to the short arm 9, the link 21 extending upwardly through the opening in the block 12 and having a spring 22 disposed between a nut 23 on the upper end thereof on the upper side of the arm. With this construction, to cause initial engagement of the pressing head and the pressing 20 bed, the foot treadle 19 is moved downwardly which will move the arm 9, arm 6, and head 10 carried thereby downwardly and this downward movement is more or less resilient due to the spring interposed between the upper surface of 25 the arm 9 and the nut 23 on the rod 21 whereby there will be no breakage of parts should some foreign material be disposed on the pressing bed or buck 1. Such downward movement of the pressing head 10 will result in movement of 30 the arm 8 outwardly to the right as shown in the drawings and cause a substantial straightening of the toggle consisting of the links 14 and arms 16 as will be apparent from Fig. 2 which will bring an extension 24 of the arm 16 beneath the lower end of a piston rod 25 that forms 35 a part of a cylinder and piston construction including a cylinder 26 and piston 27, the cylinder 26 being secured on the frame 2 and a spring 28 being provided to normally maintain the piston 27 in its uppermost position.

In the operation of this apparatus, assuming the pressure or pressing head 10 to be in opened or unoperated position as shown in Fig. 1, a garment is placed on the pressing bed or buck 50 1 with the proper lay, the inclination of the pressing bed or buck being such as to permit ready visibility of the upper surfaces of the buck or the work thereon when the pressing head 10 is disposed but a short distance thereabove and 55 a shield 29 being provided to prevent the garment from contacting with any of the operating mechanism, and pressure is exerted on the foot treadle and lever construction 19 which will cause downward movement of the pressing head 10 into engagement with the pressing bed as hereinbefore described and move the extension 24 of the arm 16 beneath the piston rod 25 whereby downward movement of the piston will cause further straightening of the toggle mechanism consisting of the links 14 and arms 16 and pressure to 60 be exerted between the pressure head 10 and the pressing bed 1. With this construction, a large degree of movement of the head 10 will be brought about by a small degree of movement of the arm 9 due to the length ratio between the short arm 9 and the head arm 6.

Such downward movement of the pressure or pressing head 9 by operation of the foot treadle and lever mechanism 19 and downward movement of the link 21 will cause a lug 30 carried

by the link 21 to contact with the operating arm of a fluid pressure valve 32 and open such valve whereby fluid pressure will be admitted to the piston and cylinder construction previously described through the fluid pressure conduit 33 whereby the piston 27 and piston rod 25 will be moved downwardly, the piston rod 25 contacting with the extension 24 on the arm 16 as shown in Fig. 2 to further straighten the toggle and bring about relatively great pressure between the pressing head 10 and the pressing bed 1. In the preferred arrangement of parts, the lug 30 does not cause opening of the fluid pressure valve 32 on its initial downward movement although such action may take place if desired. Instead, the pressing head 10 is brought into initial engagement with the pressing bed 1 prior to opening of the fluid pressure valve 32 and then the link 21 is moved slightly further downwardly by further pressure on the foot treadle and lever mechanism 19 to bring about opening of the valve 32, this action being, of course, against the resistance of the spring 22. After the pressing operation is completed, the foot treadle and lever mechanism is relieved of pressure whereupon it will be moved upwardly under the action of the spring 22 releasing the operating arm of the fluid pressure valve 32 from the lug 30 due to upward movement of the link 21 whereupon the fluid pressure valve may be closed by any suitable means, in 100 this instance, a spring, not shown, and the piston 27 may be moved upwardly by the action of the spring 28. Of course, suitable means must be provided for exhausting the fluid pressure from above the piston 27. Pressure being released 105 from above the piston 27 the pressing head 10 and all of the operating parts are returned to their normal unoperated position by the springs 22 and 28 and the weight 11.

Referring to the drawings and the preceding 110 description, it will be seen that I have provided a machine embodying numerous novel and advantageous features. For instance, I have provided a pressing machine embodying operating mechanism such that the pressure or pressing head may be moved into initial engagement or 115 cooperative relation with the pressing bed or buck by manual means and with the expenditure of very little force as well as by relatively small movement of the operating parts together with 120 means including a fluid pressure operating mechanism for exerting a very great pressure on the pressing bed or buck by the pressure or pressing head with the expenditure of very little force and movement of the operating parts through a 125 relatively short distance, the manual operating means being effective to set the fluid pressure or automatic operating means in operation. This is primarily accomplished by the use of a plurality of arms and links whose length ratio is 130 such as to cause a large degree of movement of one arm or link by a relatively small movement of another arm or link or a system of arms and links wherein a relatively small force and small amount of movement of one arm or link will 135 cause a relatively great force to be exerted by an arm or link moved thereby. Thus, very little force need be expended to cause a relatively great movement of the operating parts and a large amount of pressure between the pressing elements, the last named pressure being what is commonly termed as the final pressure or "squeeze" and that period of time when the actual pressing operation takes place.

Another novel and advantageous feature of 150

my invention resides in the fact that I have provided a pressing machine embodying a work receiving bed that is inclined at an angle from the horizontal and has its uppermost edge in the same 5 horizontal plane as the pivot of the pressing head supporting arm, a pressing head normally in separated or full open position, and operating mechanism for moving the head into pressing relation with the bed and causing a final pressure or 10 "squeeze" therebetween consisting of partly manually operated means and partly fluid pressure or automatic operating means, the manually operating means being effective during its operation to bring about operation of the automatic or fluid pressure means. Thus, I have provided a mechanism in which the means for causing the final pressure or "squeeze" between the pressing head and the pressing bed is entirely dependent on the operation of the 15 mechanism for causing initial engagement of the head and bed, which mechanism is manually operated while the mechanism for causing the final pressure or "squeeze" is an automatic or fluid pressure operating mechanism.

20 25 What I claim is:

1. A pressing machine, comprising a head and a bed normally in separated or full open position, operating mechanism for moving said head into initial engagement with said bed and for producing final pressing pressure therebetween, including a toggle operatively connected to said head and normally ineffective as a part of the head moving means, a motor means normally having no operative connection with said toggle, operator-operated means having a yielding connection with said head for moving said head into initial engagement with said bed, means for effecting an operative connection between said motor means and said toggle by movement of said head into initial engagement with said bed, and means for controlling the operation of said motor means by said same head movement.
2. A pressing machine, comprising a head and

a bed normally in separated or full open position, said head being carried by a pivotally mounted arm, operating mechanism for moving said head and bed into closed position and for producing final pressure therebetween including a motor means normally having no connection with said head, a plurality of head moving arms of different lengths operatively connected with said head carrying arm, operator-operated means having a direct connection with the shorter of said head moving arms for moving said head and bed to closed position, a toggle connected to a longer of the head moving arms and normally ineffective as a part of the head moving means, means for effecting an operative connection between said motor means and said toggle by movement of said head and bed into closed position, and means for controlling operation of said motor means by said same head movement.

3. A pressing machine, comprising a head and a bed, and means for moving said head into engagement with said bed and producing final pressing pressure therebetween, including a motor means, a plurality of pivotally mounted integral arms including a head carrying arm and head moving arms of different lengths, all of said arms having their axis of movement about the same point, operator-operated means having a connection with the shorter of the head moving arms for moving said head into initial engagement with 100 said bed, said motor means normally having no connection with the head moving arms, means for effecting an operative connection between the longer of the head moving arms and said motor means by movement of the head into initial engagement with the bed whereby the last named head moving arm may be actuated by said motor means to produce final pressing pressure between said head and bed, and means for controlling operation of said motor means by movement of the 105 parts to bring said head and bed into initial engagement.
